UNITED STATES PATENT OFFICE.

THOMAS LEGGETT STURTEVANT, OF QUINCY, AND THOMAS JOSEPH STURTEVANT, OF WELLESLEY, MASSACHUSETTS, ASSIGNEES TO STURTEVANT MILL COMPANY, OF PORTLAND, MAINE, A CORPORATION OF MAINE.

CRUSHING-MACHINE.

No. 853,656.

Specification of Letters Patent.

Patented May 14, 1907.

Application filed June 13, 1905. Renewed January 30, 1907. Serial No. 354,909.

To all whom it may concern:

Be it known that we, THOMAS LEGGETT STURTEVANT and THOMAS JOSEPH STURTEVANT, both citizens of the United States, residing, respectively, at Quincy and Wellesley, in the county of Norfolk and State of Massachusetts, have invented or discovered certain new and useful Improvements in Crushing-Machines, of which the following is a specification, reference being had therein to the accompanying drawings.

This invention relates to certain improvements on the rocking jaw crushing machines shown and described in our U. S Patents Nos. 706,575, July 19, 1898, and 777,227, December 13, 1904; the present invention having for its object to provide an improved operating mechanism for the oscillating jaw frame or lever which carries the movable jaw 20 of the crusher, and which movable jaw has a rolling crushing action on the material held between itself and the stationary jaw of the crusher.

In the accompanying drawings, Figure 1 is a plan view of our improved crushing machine and Fig. 2 is a vertical section of the same on line 2—2, of Fig. 1. Fig. 3 is a transverse sectional view of the machine in the plane of the axis of the driving shaft, looking from the right of Figs. 1 and 2.

Referring to the drawings, 12 denotes the frame of the machine which may be of substantially the same construction as in the machine shown and described in our said Patent No. 777,227. Mounted in the said frame is the driving shaft 13 carrying fly-wheels 14, the driving pulley 15 and an eccentric 16. The oscillating jaw frame or lever 17 is hung or suspended at its forward end to a cross-bar 18, supported by the frame 12, by means of a broad link 19 the lower portion of which engages a pivot bolt 20 on the jaw frame or lever 17. Mounted in the rear portion of the jaw frame or lever 17 is a roller 21 which rests upon the eccentric 16 and is forced downward against said eccentric by a suitable spring or springs 22 confined between a portion of the said jaw frame or lever 17 and a cross-bar 23 supported by the stationary frame of the machine. Against the cross-bar 23 impinge nuts 24 on vertical bolts 25, and said nuts are adjustable so that the tension of said springs may be varied. The

ends of the said springs preferably abut against bearing plates 34 having convex ribs seated in suitable lined sockets 35 in said jaw-frame or lever 17 and said cross-bar 23.

The movable or rocking-jaw 26 is preferably pivotally attached at its upper end to the forward end of the jaw frame or lever 17 and pressed against at its lower end by springs 27 encircling bolts 28 connecting the lower portion of said jaw with the lower portion of the jaw frame or lever 17, so that the said movable jaw is elastically or yieldingly mounted on the said jaw frame or lever, as will be understood. The said movable jaw 26 carries a jaw plate 29 co-operating with a normally stationary front jaw plate 30 mounted on the normally stationary block or jaw 31, which latter is, however, preferably vertically adjustable on the frame of the machine by means of screw bolts 32, as in the construction shown in our said Patent No. 777,227.

The jaw frame or lever 17 is backed against suitable abutments 36 on the stationary frame 12 by toggle links 33, as in the machines of our said patents; so that when the driving shaft 13 is rotated the eccentric 16 thereon, and against which the roller 21 bears, will cause rising and permit falling movements to be imparted to the rear end of said jaw frame in such a manner as to cause rolling crushing movements to be imparted to the movable jaw plate 29 to crush the material held in the receptacle between said movable jaw plate and the stationary jaw plate 30.

In a crushing machine of the class herein shown and described, and in which the rocking jaw frame or lever is loosely hung to the frame of the machine at its forward end, as by the link 19, and is loosely backed against the frame of the machine at its rear end, by the toggles 33, the rocking jaw has a rolling crushing action at both the upward and the downward movements of the rear end of the said rocking jaw-frame or lever; the upward movements, to cause crushing action, being effected, in the construction herein shown, by the cam or eccentric 16, and the downward movements, to cause crushing action, being effected by the springs 22 which are sufficiently stiff and powerful for this purpose. Thus in this improved machine, the

crushing operation is partly effected by the expansion of the springs 22 previously compressed at the upward stroke of the rear end of the rocking jaw frame or lever as the latter is positively lifted by the cam or eccentric 16.

The rolling movements, above referred to, of the rocking jaw 26 carried by the rocking jaw frame 17, so as to effect rolling crushing movements at what may be termed both the forward and the backward throws of said jaw, are due partly to the loose manner in which the said rocking jaw frame is loosely suspended at its forward end to the machine frame by the link 19, and partly to the manner in which said rocking jaw frame is operated by the conjoint action of the eccentric 16 and springs 22 in such a manner that the forward ends of the toggle links 33 rise and fall above and below their rear ends backing against the abutments 36; so that when material to be crushed is between the fixed and movable jaw plates the lower end of the movable plate will separate more or less from the fixed plate as the upper end of said movable plate travels forward when the machine is in crushing operation, thus producing rolling crushing action at both forward and backward movements of the rocking jaw as the rear end of the said rocking jaw rises and falls when co-operatively actuated by the said eccentric 16 and springs 22.

The improved operating mechanism for the jaw frame or lever 17 herein shown and described, and in which the movements of the said jaw frame or lever are imparted thereto by the eccentric or cam 16 and the opposing spring or springs 22, provides for more elasticity in the crushing movements of the said jaw frame or lever than in the constructions heretofore employed; so that there is less danger of breakage of the toggle links 33 or other breakable parts, when an unusual resistance is offered to the crushing action of the jaws, as when some unusually hard material is fed into the mill or accidentally gets into the receptacle between the stationary and movable jaw plates. This result is due to the fact that the springs 22 act, in a measure, as jaw relief springs, so as to yield under any excessive strain or resistance, and in this manner co-operate with the jaw relief springs 27; and even if the last-named springs were not employed the movable jaw 26, mounted on the toggle-backed 55 rocking jaw frame or lever 17, would still be more or less cushioned or relieved when exposed to excessive strain, and is doubly cushioned or relieved in the construction herein shown employing the two sets of springs 22 and 27, the amount of compression of the springs 27 being determined by the stiffness of the springs 22. For example, should a sledge hammer be accidentally dropped into the receptacle between the jaw plates there 65 would be less danger of breakage to the ma-

chine with the improved operating mechanism herein shown than in the constructions shown by our prior patents in which the rocking jaw frames or levers are operated from the driving shafts of the machines by pitmea connections with the driving eccentrics or cranks.

A still greater advantage in the novel construction, over the old, resides, however, in enabling the connecting-rod or pitman, by which the rocking jaw frame was formerly operated from an eccentric on the driving shaft, to be dispensed with, as in the use of such operating connecting-rod or pitman, the bearings thereof, if not kept in perfect adjustment, often pounded to destruction owing to the severe strain necessarily incidental to the use of the machines in which such operating connecting-rods or pitmen were employed.

While we prefer to impart positive upward movements to the rocking jaw frame or lever, by a cam or eccentric, and yielding downward movements by the spring or springs 22, it will be understood that this construction might be reversed and the upward movements be imparted to the said jaw frame or lever by springs and the downward movements by a cam or eccentric. The invention is therefore not to be understood as being limited to the details of construction herein shown, as these may be varied within the province of mechanical skill without departing from the spirit of the invention. For example, the rocking jaw plate 29 might be rigidly mounted on the rocking jaw frame or lever instead of being mounted on the yielding jaw 26, and the normally stationary front jaw plate 30 might be yieldingly mounted relative to the machine frame.

Having thus described our invention we claim and desire to secure by Letters Patent:-

1. In a crushing machine, the combination with a stationary jaw and a movable jaw co-operating therewith, of a horizontally extending rocking jaw frame or lever carrying said movable jaw, a rotating cam or eccentric for imparting crushing movements to the said rocking jaw frame or lever in one direction, and a spring or springs, compressed by said cam or eccentric, for effecting crushing movements of the said rocking jaw frame or lever in the opposite direction.

2. In a crushing machine, the combination with a stationary jaw and a movable jaw co-operating therewith, of a rocking jaw frame or lever on which said movable jaw is yieldingly mounted and which rocking jaw frame is loosely hung to the frame of the machine at its forward end and is loosely backed by toggles against the machine frame at its rear end, a rotating cam or eccentric for imparting movements to the said rocking jaw frame or lever in one direction, and a spring or

springs for effecting the movements of said jaw frame or lever in the opposite direction.

3. In a crushing machine, the combination with a stationary jaw and a movable jaw co-operating therewith, of a horizontally extending rocking jaw frame or lever carrying said movable jaw, said rocking jaw frame being loosely hung to the frame of the machine at its forward end by a link and being backed by toggles against said frame at its rear end, a roller mounted in the rear end of the said rocking jaw frame or lever, a rotating cam or eccentric against which said roller bears, and spring mechanism for effecting movements of said rocking jaw and rocking jaw frame in opposition to the movements imparted by said cam or eccentric.

4. In a crushing machine, the combination with a stationary jaw and a movable jaw co-operating therewith, of a rocking jaw frame or lever on which said movable jaw is yieldingly mounted, and which is loosely hung to the frame of the machine at its forward end and is loosely backed by toggles against the machine frame at its rear end, a roller mounted in the rear end of the said rocking jaw frame or lever, a rotating cam or eccentric against which said roller bears, and spring mechanism for effecting movements of said rocking jaw and rocking jaw frame in opposition to the movements imparted by said cam or eccentric.

5. In a crushing machine, the combination with the frame thereof, of a stationary jaw mounted on said frame, a horizontally extending rocking jaw frame or lever loosely suspended from said machine frame at its forward end and provided with a roller at its rear end, a movable jaw carried by said rocking jaw frame or lever, a rotating cam or eccentric against which said roller bears, toggles loosely backing the rear end of said jaw frame or lever against the machine frame, and spring mechanism for effecting movements of said rocking jaw frame or lever in opposition to the movements effected by said cam or eccentric.

6. In a crushing machine, the combination with the frame thereof, of a stationary jaw mounted on said frame, a rocking jaw frame or lever loosely suspended from said machine frame at its forward end and provided with a roller at its rear end, a movable jaw yieldingly mounted on said jaw frame or lever, a rotating cam or eccentric against which said roller bears, toggles loosely backing the rear end of said rocking jaw frame against the machine frame, and spring mechanism for effecting movements of said jaw or lever in opposition to the movements effected by said cam or eccentric.

7. In a crushing machine, the combination of a front jaw and a rocking lever jaw opposite the same and co-operating therewith, of a relief spring or springs for said rocking lever

jaw, a rotating cam or eccentric for imparting movements to said rocking jaw in one direction, and a spring or springs for effecting movements of said rocking lever jaw in the opposite direction, and which last-named spring or springs co-operate with the first-named spring or springs for effecting jaw relief.

8. In a crushing machine, the combination with a stationary jaw, of a movable jaw, a horizontally disposed rocking jaw frame on which said movable jaw is mounted, a cam or eccentric, a spring or springs opposing the action of the said cam or eccentric and serving to impart alternate movements to said movable jaw by being previously compressed by the operation of said cam or eccentric.

9. In a crushing machine, the combination of a front jaw, a rocking jaw opposite the same and co-operating therewith, and a horizontally extending rocking jaw frame or lever which is pivotally supported from the machine frame near its front end and which is backed at its rear end by a toggle or toggles, of a cam or eccentric and co-operating springs for imparting vibrating movements to the rear end of said rocking jaw frame or lever and rocking crushing movements to said rocking jaw.

10. In a crushing machine, the combination of a normally stationary front jaw and an opposing rocking jaw, a rocking frame or lever, a swinging link by which said rocking frame or lever is supported on the machine frame near its front end, means for movably backing the rear end of said rocking frame or lever against the machine frame, and a cam or eccentric and opposing springs for imparting vibrating movements to said rocking frame or lever carrying said rocking jaw.

11. In a crushing machine, the combination with a stationary jaw and a movable jaw co-operating therewith, of a horizontally extending and bodily movable rocking jaw frame or lever at the forward end of which the said movable jaw is mounted so as to be entirely supported thereby and the rear end of which reciprocates vertically, said rocking jaw frame or lever being provided with a bearing-roller at its rear end, a rotating cam or eccentric for imparting vertical movements to the said rear end of the said rocking jaw frame or lever in one direction, and against which cam or eccentric said roller bears, and a spring or springs, compressed by said cam or eccentric, for effecting movements of the said rocking jaw frame or lever in the opposite direction.

In testimony whereof we affix our signatures, in presence of two witnesses.
